UNITED STATES PATENT OFFICE

ALBERT C. BRAUER AND GEORGE W. WEIMER, OF GIRARD, OHIO

ROLLING MILL REPEATER

Application filed October 4, 1928. Serial No. 310,272

Our invention relates to improvements in the class of repeaters and delivery terminal conduits therefor for use as rolling mill guides. It has for its object to provide simple, efficient and durable means for effecting proper delivery of the blank in its passage from the reducing pass of one pair of rolls, around a guiding repeater or reversing mechanism, and then through one or the other of our improved delivery terminals to another reducing pass, of a second pair of rolls.

The improvement is of the same general type in certain respects as that shown in the prior patent of Weimer #1,577,412, of March 16, 1926.

In guiding mechanism of the same general kind, with a continuous blank of the flat strip type subjected to continuous serial reduction, and involving return pass guiding mechanism, a torsional twist is ordinarily imparted to the blank, tending to vary its delivery position on entering the next subsequent pass for the following reduction, either edgewise or flatwise.

Our improvement herein relates particularly to guiding and controlling means by which the blank may be positively delivered to the pass of the reducing rolls continuously in the desired position.

This object is effected by our improvement by so constructing the delivery terminal, leading to the pass, in such a manner that it will automatically deflect the blank from an entering position, and in harmony with or opposition to any torsional movement imparted to it in passing around the repeater. These objects are effected, in certain preferred constructions, by means of the mechanism herein illustrated and as further described.

Referring to the drawings showing such preferred constructions:

Fig. 1 is a plan view showing the application of the terminal mechanism to the receiv-

ing grooves of a pair of rolls, for edge rolling;

Fig. 2 is a longitudinal vertical sectional view on the line II—II of Fig. 1;

Fig. 3 is a view in elevation of the delivery end of the terminal of Figs. 1 and 2;

Fig. 4 is a cross section on the line IV—IV of Fig. 2 in the direction of its delivery end;

Fig. 5 is a cross section on the line V—V of Fig. 1 of one member of our improved adjustable repeater;

Fig. 6 is a similar view on the line VI—VI of Fig. 1 showing the adjustable telescoping connection between the two repeater member sections;

Fig. 7 is a plan view similar to the delivery end construction of Fig. 1, showing a modified form of delivery terminal for flatwise delivery;

Fig. 8 is a longitudinal vertical sectional view on the line VIII—VIII of Fig. 7;

Fig. 9 is a horizontal sectional view on the line IX—IX of Fig. 8;

Fig. 10 is a view in elevation of the delivery end of the terminal of Fig. 8;

Fig. 11 is a cross section on the line XI—XI of Fig. 8;

Fig. 12 is an inclusive diagrammatic view showing successive positions of the blank in emerging from the delivery terminal.

In the drawings, 2 and 3 are the first and second sets of rolls for delivering the blank to and receiving it from the repeater and terminal delivery mechanism respectively, such mill for present purposes being designed for edge rolling.

The receiving section 4 of the repeater is of trough form, into which the blank enters, a guide 5 of any suitable construction being utilized between its receiving end and the pair of rolls 2, if desired. The companion section 6 of the repeater effects a continuation of section 4, providing for U-shaped return of the blank in a reverse direction, and

delivery into our improved delivery terminal 7.

Sections 4 and 6 are generally trough-shaped as shown, the end of one being telescoped within the other and adapted to be adjusted inwardly or outwardly thereof, and there held by means of a countersunk connecting bolt 8 extending through the bottom wall of repeater 4 and through one of a series of holes 9 in the bottom of repeater 6, as clearly shown in Figs. 1 and 6.

By such means the repeater may be adjusted to accommodate its lateral width and pass position, to the several active grooves of the two sets of rolls, as will be readily understood.

The repeater and the terminal delivery mechanism are mounted upon any suitable base plate or support, not necessarily herein shown.

The outer walls 10 of sections 4 and 6, against which the blank most forcibly bears in its passage therethrough, are turned inwardly at their upper portions, as indicated at 11. They thus more effectively assist in retaining the blank in its passage, while also imparting a tipping tendency to it, causing the blank to enter the delivery terminal 7 in a partially tipped or tilted position edge-wise, as indicated at *a*, Fig. 12.

The delivery terminal 7, as shown, is mounted upon and made part of a supporting base 12, between which and the delivery end of section 6 of the repeater we provide a ball and socket joint, connected by a bolt 13, facilitating further lateral and vertical adjustment where necessary.

For such purpose the bottom plate 12 extends rearwardly and is provided with a socket groove 14 having a part spherical rear terminal into which seats the bulbous downward projection 15 on the bottom forward end portion of section 6. Upwardly thereabove extends a rounded coping or housing 16 of funnel formation, having an upwardly arched coping top or wall and completely enclosing the delivery opening of the side walls of section 6, as clearly shown in Figs. 1 and 2.

The base 12 is also provided with a comparatively short upwardly arched receiving and delivery channel within coping 17, preferably made integral with the base and adapted to deliver the blank directly into the terminal 7, as shown.

Said terminal, in the construction shown in Figs. 1 to 4 inclusive, consists of two side members 18 and 19 respectively, each of which bears by its lower edge against the upper surface of base 12 and to which it is secured by bolt connections 20 and 21 through laterally extending lugs on said members and the base respectively. Side member 18 extends upwardly and over to the other side, resting by its terminal edge upon side mem-

ber 19 and thus providing a continuous rounded upper wall 22 of one of the side members, as clearly shown in Fig. 4.

The inner wall faces of each member 18 and 19 respectively are transversely deflected for a portion of their length, between their receiving and delivery terminals, as at 23, tending to effect lateral deflection of the blank as it passes through the terminal, toward its vertical delivery slot 24. Such slot is provided by the oppositely spaced inner side wall faces of sides 18 and 19, so that as the blank emerges therefrom it is in proper vertical position for entrance between the edging passes of rolls 3, as at *b*, Fig. 12, either with or without an intervening guide 25, like guide 5.

It will be understood that the spacing of the side members 18 and 19 may be accurately regulated to suit the particular size of blank being treated, with proper clearance for good practice.

When it is desired to deliver the blank flatwise, for flat rolling between a pair of smooth-faced rolls 3a, as in Fig. 7, we utilize a modified construction such as illustrated in Figs. 7 to 11 inclusive. In such construction the same base 12 is utilized with its ball and socket joint connection above described, but the base is provided with additional features, permitting for supplemental adjustment of lateral wings, to wit, slots 26 of sufficient length at each side extending through correspondingly located lugs, as shown.

The delivery terminal member 7a in such case consists, as before, of two interfitting members. These, however, comprise an outer and upper coping member 18a and an inner under member 19a. These, as shown, are of tapering form throughout their length, and are of gradually rounded spirally shouldered contour, tending to gradually throw the blank over for flatwise delivery. In such case we preferably provide interior deflecting means, causing the blank to turn axially upon itself in a spiral direction, continuing the general deflecting tendency effected by the U-shaped bend of the repeater, in which the blank tends to lay over sideways as it passes therethrough.

The top and bottom inner surfaces of walls 18a and 19a at the receiving end of delivery terminal 7a are annular, arching around the opening above the flattened bottom. They taper, as shown, toward each other, narrowing together vertically and with ample width laterally to accommodate the flatwise delivery position of the blank, between such upper and lower surfaces, as in Fig. 10.

The inner curved wall of upper member 18a has an inward deflecting swell or shoulder *e* along one upper side, diagonally opposite a similar co-acting shoulder *f* along the inner wall of lower member 19a. The

spirally curved wall of member 18a merges into a flat delivery lip face 28, while the inner curved surface of member 19a merges in a similar manner into a lower flat delivery lip 29.

5 For the purpose of positively guiding and delivering the blank in a flatwise position, the end of the upper wall is thus flattened and spaced above the flattened lower wall, with proper clearance. We also provide the supplemental delivery wings or gates 27 which form, by their inner surfaces, continuations of the inner side walls of members 18a and 19a.

10 15 By such construction we provide upper and lower substantially parallel faces at the outlet end of the delivery terminal, between which the blank emerges.

Guide wings 27 are provided with rear rounded terminal bearing edges 30 bearing backwardly against correspondingly recessed receiving sockets 31 in the forward overlapping side edge portions of outer member 18a, whereby the wings may be moved inwardly or 25 outwardly therein in the manner of hinges.

Each wing is provided with a lateral lug 32 through which, by bolt 33, the wing may be secured in its slot 26 in the desired position, so as to locate the terminals of the wings at 30 the proper distance apart to provide the necessary outlet opening space, with proper clearance and confining action.

35 As thus constructed, and when properly adjusted to suit the strip being rolled, it will pass through the repeater 4—6 and copings 16 and 17, under the continuing twisting action. Such action will tend to throw it over and down flatwise in the directions indicated at *c* and *d* of Fig. 12, whereby to 40 emerge in a proper flatwise position for entrance between the flat face rolls 3a, as assisted and controlled by the terminal 7a.

It will be observed that by each of the constructions above described, we provide for 45 positive guiding and twisting of the blank, and without any liability to jamming or obstruction, while avoiding the undesirable objections of vertical slots between the side members of the terminal. Thus, in both constructions, the joints between the two members forming the delivery terminal are lateral rather than vertical, thus providing continuous integral upper and lower surfaces in a general longitudinal direction throughout, greatly assisting in free passage and unrestricted delivery of the blank to the rolls.

The general proportions, detail construction, size, or other features may be variously changed or modified by the skilled mechanic 50 or designer to adapt the invention to various conditions present in rolling mill practice, but all such changes are to be understood as within the scope of the following claims.

What we claim is:—

65 1. In combination with the delivery end of

a repeater trough for rolling mills, a delivery terminal composed of two interfitting shell members joined by a lateral seam providing inner upper and lower continuous bearing faces, one of said members having its inner 70 face inwardly deflected for action on a rolled section passing therethrough.

2. In combination with the delivery end of a repeater trough for rolling mills, a delivery terminal composed of two interfitting 75 shell members joined by a lateral seam providing inner upper and lower continuous bearing faces and having inner terminal faces parallel to each other providing a guiding delivery slot for the section being rolled. 80

3. In combination with a base plate having a ball joint socket, a repeater trough flexibly connected with the socket, and a two-part delivery terminal shell secured to the base plate and provided with endmost inner parallel 85 faces providing a delivery slot.

4. In combination with a base plate having a rear receiving coping and lateral attaching lugs, a two-part delivery shell connected with said lugs and provided with inner guiding 90 walls and endmost inner parallel faces providing a delivery slot.

5. In combination with a base plate having a rear receiving coping and lateral attaching lugs, a two-part delivery shell connected with 95 said lugs and provided with inner guiding walls and endmost laterally adjustable walls providing a variable width delivery slot.

6. In combination with a base plate having at its rear end a guiding coping and at its forward end laterally extending slots, a two-part delivery shell mounted on the base provided with hinged side wall extensions and means for variably holding the extensions 100 engaging said slots. 105

7. In combination with a base plate having at its rear end a guiding coping and at its forward end laterally extending slots, a two-part delivery shell mounted on the base provided at the front with hinge bearings, and side wall tongue extensions engaging said 110 bearings and provided with bolts engaging said slots.

8. A guiding terminal for rolling mills adapted to receive a blank at one end and deliver it to reducing rolls consisting of a supporting base and a two-part tapering shell mounted thereon, said shell having a laterally arranged joint whereby to provide upper and lower continuous inner wall surfaces, and having a portion of its inner wall deflected 115 tending to direct a blank passing through the terminal into correct operative relation with the pass of the rolls. 120

9. A guiding terminal for rolling mills 125 adapted to receive a blank at one end and deliver it to reducing rolls consisting of a supporting base and a two-part tapering shell mounted thereon, said shell having a laterally arranged joint whereby to provide up- 130

per and lower continuous inner wall surfaces, and having a portion of its inner wall deflected tending to direct a blank passing through the terminal into correct operative relation with the pass of the rolls, and having supplemental laterally adjustable side guiding wings at its delivery end.

In testimony whereof we hereunto affix our signatures.
